UNITED STATES PATENT OFFICE

DAMARIS BUSTANOBY, OF TEANECK, NEW JERSEY

DESIGN FOR A COMBINED SERVING TRAY AND GAME BOARD

Application filed September 1, 1932. Serial No. 44,735. Term of patent 14 years.

To all whom it may concern:

Be it known that I, DAMARIS BUSTANOBY, a citizen of the United States, and resident of Teaneck, county of Bergen and State of New Jersey, have invented a new, original, and ornamental Design for Combined Serving Tray and Game Board, of which the following is a specification, reference being had to the accompanying drawing, forming part thereof.

Fig. 1 is a plan view of a combined serving tray and game board showing my new design, and Fig. 2 is a diagrammatic longitudinal section thereof.

I claim:

The ornamental design for a combined serving tray and game board as shown.

DAMARIS BUSTANOBY,
